Primary Examiner — Michelle E. Wilson*Assistant Examiner* — Sanjeev Paul(74) *Attorney, Agent, or Firm* — Wolf, Greenfield &
Sacks, P.C.(57) **CLAIM**The ornamental design for an eyewear lens, as shown and
described.

DESCRIPTION

FIG. 1 is a top, front, left side perspective view of the

eyewear lens according to our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dot-dash broken lines represent boundaries of the claim
and form no part of the claimed design.The oblique shade lines show a transparent, reflective, or
shiny surface, and not surface ornamentation.**1 Claim, 3 Drawing Sheets**(56)
